UNITED STATES PATENT OFFICE.

ELLEN J. JOY, OF STOOPS, PENNSYLVANIA.

DESIGN FOR A PAIL.

SPECIFICATION forming part of Design No. 28,326, dated March 1, 1898.

Application filed January 8, 1898. Serial No. 666,110. Term of patent 14 years.

To all whom it may concern:

Be it known that I, ELLEN J. JOY, a citizen of the United States, residing at Stoops, in the county of Allegheny and State of Pennsylvania, have invented and produced a new and original Design for a Pail, of which the following is a specification, reference being had to the accompanying drawings, forming a part thereof, in which—

5 Figure 1 is a perspective view of a pail embodying the features of my design, and Fig. 2 is a vertical section through the pail on the line 2 2 of Fig. 1.

10

The design consists in a round pail having its interior embellished by a tapering fluted panel.

I claim—

The design for a pail herein shown and described.

ELLEN J. JOY.
